United States Patent Office.

WILLIAM W. WAKEMAN, JR., OF NEW YORK, N. Y.

Letters Patent No. 65,621, dated June 11, 1867.

IMPROVED LAMP FOR BURNING OFF PAINT.

The Schedule referred to in these Letters Patent and making part of the same.

TO WHOM IT MAY CONCERN:

Be it known that I, WILLIAM W. WAKEMAN, Jr., of the city and county of New York, and State of New York, have invented certain new and useful improvements in Paint-Burning Lamps; and do hereby declare that the following is a full and exact description thereof.

My apparatus is constructed so as to project the flame of any inflammable fluid horizontally, or nearly so, upon any painted surface.

I will first describe the construction of my apparatus, and will afterwards designate the points which I believe to be new.

Figure 1 represents a longitudinal vertical section on the line x x , and a side elevation from x to x' in fig. 2.

Figure 2 is a plan view of the apparatus.

A is a reservoir of copper or other metal, having a bottom, B, and sides C, here represented as a hemisphere, securely fastened together. A neck, D, communicates with the reservoir A. E is a stopper in the neck D. F is a pipe, which passes through the upper portion of the reservoir A, and terminates inside with an expanded mouth, G, to prevent the alcohol from flowing in when the apparatus is tilted. The lower end of the pipe F passes through the wall H of the apparatus, and terminates in a small open end, I, centrally located. H is a cylindrical wall, and is virtually a continuation of the sides C of the reservoir A. This wall is extended sufficiently below the bottom of the reservoir A to receive the lamp L, which passes through, and, by means of pins, rests upon, the flange J, attached to the walls H. A portion of the wall H is cut away at M to allow a free passage for the flame from the pipe at I. K is a handle. L is an independent lamp, furnished with a tube, W, for a wick. This tube unscrews to allow the lamp to be filled. N are legs for the apparatus to rest upon.

Operation.

The reservoir A is nearly filled with alcohol through the neck D, which is then securely corked by the stopper E or its equivalent. The lamp L is then filled, a wick inserted and lighted. The flame from the lamp L strikes upon the bottom B of the reservoir A, and, heating the alcohol therein contained, raises a vapor, which, rushing out violently through the pipe F, is ignited by means of the flame from the lamp L, and thus projects a stream of flame, which may be thrown in any direction desired.

I will now state the great advantages which this apparatus possesses: first, in the simplicity of the mode of construction; second, in the removal of all danger from fire caused by the accidental upsetting of the apparatus; third, in shielding the flame more effectually from the wind; fourth, in the instant suspension of the flame by removing the lamp L; fifth, in the increased capacity and lengthened duration of the action of the apparatus; sixth, in the absolute protection to the mouth of the pipe I and the lamp flame L from the paint scrapings; seventh, in its increased usefulness consequent upon the greater angle at which the flame can be thrown; it will even burn paint off the floor.

Having now fully described my invention, what I claim as new therein, and desire to secure by Letters Patent, is as follows:

1. The reservoir A, placed over the lamp L, substantially and for the purposes herein set forth.
2. The expanded mouth G of the pipe F, or its equivalent, substantially as herein described.
3. The independent lamp L, operating substantially as and for the purpose herein specified.

W. W. WAKEMAN, JR. [L. S.]
